Primary Examiner — Richard E Chilcot(74) Attorney, Agent, or Firm — Santangelo Law Offices, P.C.(57) CLAIM

The ornamental design for a sport training mat, as shown and described.

DESCRIPTION

FIG. 1 is a top plan view of a sports training mat showing my new design;

FIG. 2 is a bottom plan view thereof;

FIG. 3 is a longitudinal side view thereof;

FIG. 4 is a lateral side view thereof;

FIG. 5 is a top plan view showing an alternative embodiment of my new design for a sports training mat;

FIG. 6 is a bottom plan view thereof;

FIG. 7 is a longitudinal side view thereof; and,

FIG. 8 is a lateral side view thereof.

The broken lines in the drawings are for the purposes of showing portions of the sports training mat that form no part of the claimed design.
